MACHINE FOR OPERATING UPON SOLES

Norwood H. Knowlton, Rockport, Mass., assignor
to United Shoe Machinery Corporation, Paterson, N. J., a corporation of New Jersey

Application October 15, 1935, Serial No. 45,110

14 Claims. (Cl. 12—27)

This invention relates to improvements in machines for operating upon soles and is herein illustrated as embodied in a channeling machine of the type in which the marginal portion of a sole is advanced continuously past operating tools by means of a work supporting feed wheel. These tools, which may comprise, for example, a channel knife and a grooving tool, are, in the illustrated machine, carried upon a head which is 5 movable upwardly and downwardly in response to the thickness of the work, the operating tools being gaged from the upper surface of the work by a presser foot. The head is urged downwardly by a spring, causing the presser foot to 10 remain in engagement with the work and also to press the work against a feed wheel. Machines of this type may be used for channeling and grooving outsoles for McKay sewed shoes.

The general object of the present invention is 20 to improve the construction of such machines for the purpose of making the machines more efficient and reliable in operation.

In accordance with a feature of the invention the head upon which the operating tools of the 25 illustrated machine are mounted is carried by an upper frame member which is detachable from the lower or principal portion of the frame of the machine, this upper frame member being secured fixedly upon the lower frame member in a desired 30 position of adjustment transversely of the direction in which the work is fed. Such provision for the adjustment of the upper frame enables the position of the operating tools transversely of the direction of the feed to be conveniently de- 35 termined.

In accordance with another feature of the invention the feed wheel is provided with elongated teeth extending from its periphery, each of the teeth having a ridge which extends lengthwise of 40 the tooth and which is convex in longitudinal section. In the illustrated machine the teeth are disposed obliquely to their path of movement. Teeth of such form not only tend to urge the work transversely against the edge gage as it is 45 being fed but also facilitate turning of the work about the more sharply curved portions such as at the ball line or at the toe without tearing the fibres of the material of the sole.

The invention further includes improvements 50 in the general organization of machines of this type, improved means for supporting the grooving instrumentality, and other features of construction and combinations and arrangements of 55 parts hereinafter described, the advantages of

which will be obvious to those skilled in the art.

In the accompanying drawings,

Fig. 1 is a view in side elevation of the improved machine;

tion of a feed wheel having a third form of tooth;

Fig. 26 is a perspective view of a portion of the periphery of the wheel shown in Fig. 25; and

Fig. 27 is a sectional view taken in a plane normal to the ridge of one of the feed teeth shown in Figs. 25 and 26.

The operating instrumentalities of the illustrated machine consists of a knife 10 for forming a channel in an outsole and a tubular knife 12 for forming the usual stitch-receiving groove at the root of the channel lip. A toothed feed wheel 14 advances the sole past the channeling and grooving knives. A driven roll 16 engages the edge of the sole to gage the sole relatively to the knives. A pressure foot 18 holds the sole in firm engagement with the feed wheel 14 and also controls the heightwise position of the knives relatively to the sole.

The supporting structure of the machine comprises a base plate 20 adapted to be secured upon a work bench. Integral with the plate 20 is a vertical guideway 22 in which may be secured in any desired position of heightwise adjustment a frame 24. The frame 24 carries the operating instrumentalities above referred to, and it is made heightwise adjustable to enable the operator to bring to a convenient level the locality at which the work is presented. Mounted directly upon the frame 24 are a shelf 23 (Fig. 2), and guard plates 25 and 27 for the feed wheel 14.

The driving mechanism for the feed wheel 14 and gage roll 16 is carried by the frame 24 and comprises a pulley 26 adapted to be driven from any suitable source of power and mounted for free rotation upon a stationary shaft 28 which is secured to the frame 24. Integral with the pulley 26 is a clutch disk 30. Also mounted for free rotation upon the shaft 28 is a clutch member comprising a hub 32 carrying a disk 34 which in the illustrated construction consists of bakelite molded to provide a rim 36 which enables the disk to be employed as a hand wheel when it is desired to turn the machine slowly by hand. A bearing 38 for taking end thrust from the hub 32 is carried by the frame 24. Secured upon the disk 34 are a plurality of leather clutch members 40 which are engageable with the face of the clutch disk 30. A spring 42 normally holds the face of the disk 30 out of engagement with the clutch members 40.

When it is desired to start the machine running the clutch disk 30 is brought into engagement with the clutch members 40 by a treadle-operated mechanism comprising an idler roll 44 which exerts axial pressure upon a hub cap 46 of the pulley 26. The roll 44 is mounted in the upper end of a lever 48 which is slotted to embrace the upper end of a lever 50. The lever 48 is pivotally connected to the lever 50 by a pin 52. A compression spring 54 surrounds a pin 56 which is threaded into the upper end of the lever 50, the spring 54 being interposed between a washer 57 abutting the head of the pin 56, and a washer 59. The washer 59 engages the lever 48 on each side of the slot formed therein to transmit the thrust of the spring 54 into the lever 48. The lever 48 thus constitutes a yieldable extension of the lever 50. The elongation of the spring 54 is limited by the engagement of the washer 59 with the lever 50. The pressure of the spring 54 can be adjusted as desired by turning the threaded pin 56. The lever 50 is fulcrumed upon a pin 58 which may be clamped in any desired position of heightwise adjustment in a slot 61

formed in a bracket 60 secured to the base plate. The pin 58 is adjusted up or down in the slot 61 to bring the roll 44 into proper relation with the hub cap 46, the level of the hub cap 26 depending upon the heightwise adjustment of the frame 24. A stop screw 62 threaded in the lever 50 adjustably limits the outward movement of the lever 50 by engaging a flange 64 of the bracket 60. As shown in Fig. 1, the flange 64 extends vertically so as to be engageable with the stop screw 62 regardless of the heightwise adjustment of the fulcrum 58. The stop screw 62 is retained in its position of adjustment by a set screw 63.

The lever 50 has an arm 66 connected at its free end to the upper end of a treadle rod 72. In order to compensate for the heightwise adjustment of the fulcrum pin 58, the arm 66 may be adjusted relatively to the lever 50. To provide for such adjustment the arm 66 and the lever 50 are pivotally connected to each other by a pin 68, the arm and the lever each having a hub, which hubs are provided, respectively, with radially extending depressions and projections 70 adapted to intermesh. Adjustment is effected by loosening the pin 68, separating the two hubs, rotating the arm 66 to bring its free end to the desired level, and then tightening the pin 68 to bring the two hubs into clamping position. The lower end of the treadle rod 72 is connected to a treadle 74. A spring 76 secured at one end to the arm 66 and at its opposite end to the work bench serves to hold the arm 66 and the treadle 74 normally in upward position with the clutch disk of the driving pulley out of engagement with the clutch members 40.

The treadle 74 controls the starting and stopping of the machine. Depression of this treadle rotates the lever 50 in a counterclockwise direction, as viewed in Fig. 1, and, through the spring 54, causes the roll 44 to bear yieldingly against the hub cap 46 and bring the clutch disk 30 into engagement with the clutch members 40. A spring-pressed latch 71 relieves the operator of having to hold down the treadle during the operation. It will be noted that the pressure between the clutch members 40 and the disk 30 depends upon the adjustment of the spring 54. The pressure of the spring 54 should be so adjusted as to enable the clutch members 50 to drive without slipping when a sole is being operated upon. However, the pressure of the spring 54 should be only slightly in excess of what is necessary, so that the operator can at once slow down or stop the machine by grasping the rim 36. Manual control in this manner is frequently more convenient than hand feeding with the clutch members disengaged.

The drive is transmitted from the hub 32 through a gear 78 which is secured upon the hub 32 and which meshes with an idler gear 80 (Fig. 7) mounted upon a stud 82 secured in the frame 24. The idler gear 80 drives a gear 84 which is fixed upon a shaft 86 by a set screw 88. Because of the idler gear 80, the direction of rotation of the hand wheel 34 will be the same as that of the feed wheel 14, an arrangement which facilitates manual drive or manual control of the drive.

The shaft 86 is journaled in the frame 24 and has an end extending outside the frame upon which there is secured by a set screw 89 a hub 90 (Fig. 3). The hub 90 carries a beveled gear 92. Secured by screws 94 to the outer face of the gear 92 is the feed wheel 14. One or more spacing members 96 may be interposed between the feed

wheel 14 and the gear 92. Secured upon the shaft 86 is a collar 98 (Fig. 1) against which bears one end of a compression spring 100 which surrounds the shaft 86. The opposite end of the spring 100 bears against a portion of the frame 24, the spring thereby tending to urge the shaft 86 and the feed wheel outwardly or to the left, as viewed in Fig. 1. The limit of such outward movement is determined by mechanism, later to be described, which operates upon the gear 84 through a washer 102 which is secured upon the face of the gear to take the wear.

The arrangements for supporting and driving the edge gage roll 16 will now be described. Formed in the frame 24 is a guideway 104 (Fig. 9) for a slide block 106 which is free to move in a direction parallel to the shaft 86. Secured in the outer end of the block 106 by a set screw 108 is a sleeve 110 upon which is rotatably mounted a beveled gear 112 adapted to mesh with the gear 92. The gage roll 16 is threaded upon the hub of the gear 112 against a spacing washer 114 of desired thickness. A hub cap 116 is countersunk into and soldered to the upper end of the hub of the gear 112. A pin 118 having a rounded head 120 which rests upon the upper surface of the cap 116 extends downwardly through the cap 116 and through the sleeve 110. Clamped upon the lower end of the pin 118 by a set screw 122 is an L-shaped block 124 having a flange 126 which extends upwardly into a slot 128 formed in the outer end portion of the slide block 106. The purpose of the flange 126 is to prevent turning of the pin 118 with the gear 112. Surrounding the pin 118 and housed within the sleeve 110 and interposed between the cap 116 and a shoulder on the sleeve 110 is a compression spring 130 which tends to raise the gear 112 and the gage roll 16 relatively to the sleeve 110 and the slide block 106. The height to which the gage roll 16 may rise under the influence of the spring 130 is controlled by a foot 132 for a purpose which will later be described. The head 120 serves as a bearing for the foot 132 and also, in combination with the pin 118 and the block 124, as a stop for limiting the upward movement of the gage wheel 16. A guard 134 (Figs. 3 and 8) extends into the space between the upper portion of the feed roll 14 and the forward portion of the gage roll 16 to prevent the work piece from being caught between these two wheels. The guard 134 is secured to the slide block 106 by a set screw 136.

The slide block 106 is retained in the guideway 104 by a cover plate 138 (Fig. 3) in which is formed a slot 140 to accommodate a pin 142 which extends into the slide block and which serves as a means for urging the slide block inwardly or toward the right, as viewed in Figs. 3 and 9, for a purpose which will later be described. Threaded into the slide block and extending parallel to the shaft 86 is a rod 144, having a capstan head 146 (Fig. 1) in which are formed holes 148 to accommodate a tool for turning the rod 144 to adjust it longitudinally with respect to the block 106. The rod 144 is retained in adjusted position relatively to the block 106 by a set screw 150. The rod 144 is slidably retained within a lug 152 extending from the frame 24. A coil spring 154 surrounds the rod 144, having one end abutting against the lug 152 and its opposite end abutting against the slide block 106 to urge the slide block outwardly or toward the left as viewed in Figs. 1 and 9. The shoulder which occurs at the junction of the head 146 with the rod 144 bears against the

opposite surface of the lug 152 to limit the outward movement of the rod 144 and thereby of the gage roll 16. The end of the head 146 bears against the washer 102 and thus determines the outward position of the shaft 86 and the feed wheel 14 under the influence of the spring 100.

Fulcrumed upon a pin 156 which is secured in the frame 24 is a bell-crank lever, one arm 158 of which is connected to a treadle rod 160 and the other arm 162 of which is engageable with the pin 142. The lower end of the rod 160 is secured to a treadle 164. Extending from the arm 158 is a lug 166 through which is threaded a stop screw 168 the end of which bears against a stationary lug 170 extending from the frame 24 to limit the movement of the bell-crank comprising the arms 158 and 162. Upon depression of the treadle 164 the arm 162 will urge the pin 142 inwardly or toward the right, as viewed in Figs. 1 and 9, against the pressure of the spring 154. This will move the gage roll 16 inwardly and also by reason of the fact that the head 146 bears against the washer 102 will cause the shaft 86 to be moved inwardly carrying with it the feed wheel 14. The inner position assumed by the feed wheel 14 and the gage wheel 16 upon depression of the treadle 164 is determined by the adjustment of the stop screw 168. The proper positioning of the gears 92 and 112 relatively to each other is obtained by loosening the set screw 150 and turning the head 146 to adjust the gage roll inwardly or outwardly with respect to the rod 144. The pressures of the springs 100 and 154 normally hold the feed wheel and the gage roll respectively in their outermost positions with the treadle 164 up. The normal position (i. e. the position when the treadle is up) of the gear 84 is always the same being determined by the capstan head 146 which bears against the fixed lug 152. The feed wheel 14, however, may be adjusted inwardly or outwardly upon the shaft 86 by loosening the set screw 89. The spring 100 is relatively light to avoid excessive wear between the washer 102 and the capstan head 146.

Detachably mounted upon the upper portion of the frame 24 is a frame 172. Threaded into the frame 172 (Fig. 6) is a clamping screw 174 having a winged head 176 and having also a flange 178 for exerting clamping pressure against two spaced lugs 180 extending upwardly from the frame 24. The frame 172 has a finished surface 182 which is adapted to enter into clamping engagement with the opposite surfaces of the lugs 180 upon tightening of the screw 174 to hold the frame 172 securely clamped upon the frame 24. The lugs 180 are undercut, as indicated by the numeral 183 on Fig. 6, to hold the frame 172 more securely in position. The frame 172 can readily be detached from the frame 24 by loosening the screw 174 sufficiently to enable the surface 182 to be withdrawn from beneath the undercut surfaces 183. An inward and outward adjustment for the frame 172 is obtained by loosening the screw 174 and sliding the frame 172 inwardly or outwardly to the desired position. In order to facilitate such adjustment a screw 184 having a capstan head 186 is threaded into a lug 188 extending from the frame 172. A groove 190 is formed in the head 186 and is engaged by a stationary member 192 secured by a screw 193 in one of the lugs 180. Turning of the head 186 while the clamping screw 174 is loosened will adjust the frame 172 inwardly or outwardly, and when the desired adjustment has been effected the screw 184 is clamped by a set screw 194.

The clamping screw 174 is then tightened. The frame 172 can thus always be replaced in its adjusted position upon the frame 24 as long as the adjustment of the screw 184 has not been changed.

Extending laterally from the head 172 and integral therewith is an arm 196 (Figs. 2 and 18) the outer end portion of which carries a pin 198 having its axis substantially parallel to that of the feed wheel 14. Fulcrumed upon the pin 198 is a lever 200 the free end portion of which constitutes a head 202 which supports the channeling and grooving knives. The head 202 is provided with surfaces 203 (Fig. 18) which bear against the outer end of the frame 172. The head 202 is retained in engagement with the frame 172 by a guide 204 (Fig. 18). Fulcrumed upon a pin 206 secured in the frame 172 is a lever 208 having formed in it a cup-shaped depression 210. Extending through the lower wall of the depression 210 and threaded into the frame 172 is a screw 212 having a knurled head 214. Surrounding the screw 212 and interposed between the head 214 and the bottom surface of the depression 210 is a compression spring 216. Interposed between depressions formed respectively in the under surface of the outer end portion of the lever 208 and the upper surface of the head 202 is a strut 218. The pressure of the spring 216 acting through the strut 218 urges the head 202 downwardly as far as permitted by a stop screw 220 (Fig. 4) which is threaded through a lug 222 extending from the lever 200. The end of the stop screw 220 bears against the upper surface of the arm 196. The screw 220 is provided with a knurled head 224. Surrounding the screw 220 and interposed between the head 224 and the lug 222 is a compression spring 226 which serves to hold the screw 220 against accidental turning, thereby retaining it in a position of desired adjustment.

The mounting of the presser foot 18 in the head 202 will now be described. Guided for movement in vertical adjustment in a rectangular notch in the head 202 is a block 228 (Figs. 1 and 2) of rectangular cross section. The block 228 is secured to the head 202 by a clamping screw 230 which passes through a vertical slot in the block 228. In the lower portion of the block 228 is formed a horizontal guideway in which the presser foot 18 is slidably mounted for horizontal adjustment in the direction of feed of the work. The presser foot is secured in its adjusted position relatively to the block 228 by a clamping screw 232 which passes through a horizontal slot in the presser foot 18. In order to facilitate vertical adjustment of the presser foot 18 relatively to the head 202 an adjusting screw 234 is threaded into the block 228. The screw 234 has a knurled head 236. A collar 238 integral with the shank portion of the screw 234 engages a notch formed in the head 202 to hold the screw 234 against vertical movement relatively to the head 202. Turning of the knurled head 236 will, therefore, serve to raise or lower the presser foot 18. The lower portion of the presser foot 18 has a smooth surface which rides upon the upper surface of the work piece and which is rounded off, as indicated by the reference character 240 on Fig. 2, to accommodate the advancing work piece.

The presser foot 18, as has already been mentioned, rests upon the work piece, and its pressure upon the work piece represents not only the

total weight of the head 202 and all parts carried thereby but also the force of the spring 216. The stop screw 220, which serves to keep the channeling and grooving knives out of contact with the feed roll 14 when no work is passing through the machine, is adjusted to enable the presser foot to approach the feed roll 14 more closely than the minimum thickness of the work which is to be treated. During the passage of work the heightwise position of the channeling knives will be determined by the presser foot 18 and not by the stop screw 220.

The head 202 may be raised by a treadle mechanism comprising a lever 242 (Figs. 1 and 4) which is fulcrumed upon a pin 244 secured in the frame 24. One end of the lever 242 engages a lug 246 extending downwardly from the arm 200. Secured to the opposite end of the lever 242 is a rod 248 the lower end of which is secured to a treadle 250. The depression of the treadle 250 will thus operate to raise the head 202. When the channeling cut is to begin at one side of the heel end of a sole and terminate at the other side of the heel end it is unnecessary to raise the head 202 inasmuch as the feed wheel will carry the sole under the presser foot, and the head will yield upwardly according to the thickness of the sole. However, in many types of work the channeling cut begins and terminates at localities between the ends of the sole, for example, at the heel breast line. In such cases the sole is introduced between the presser foot and the feed wheel with the head raised, the head being lowered to bring the knives into operating position at the locality at which the channel is to begin, and being raised again when the knives have reached the locality at which the channel is to terminate.

The arrangements whereby the channeling knife 10 is secured in the head 202 will now be described. Slidably mounted in a vertical guideway formed in the head 202 and retained therein by a cover plate 251 (Figs. 3 and 18) is a slide block 252. Threaded into the upper portion of the block 252 is an adjusting screw 254 having a square head 255. The upper portion of the shank of the screw 252 is smooth and passes through a bore in a lug 256 extending from the head 202. A collar 258 upon the screw 254 bears against the upper surface of the lug 256 preventing downward movement of the screw 254. Surrounding the screw 254 and interposed between the under surface of the lug 256 and the upper surface of the block 252 is a compression spring 260 which exerts a downward thrust upon the block 252 to maintain the block yieldingly in a position of adjustment determined by the screw 254. Formed in the lower portion of the block 252 is an arcuate guideway 262 (Fig. 11) in which is slidably mounted a block 264. The block 264 is secured in a desired position of angular adjustment in the guideway 262 by a clamping bolt 266 (Fig. 3) which is threaded into the block 264 and which passes through a slot in the block 252. The under surface of the block 264 is formed to constitute a horizontal guideway parallel to the direction of feed of the work for a block 268 which is secured in adjusted position to the block 264 by a clamping bolt 270. A slot 272 parallel to the direction of feed of the work is formed in the block 268 to accommodate the bolt 270 for various positions of adjustment. Formed in the block 268, as shown in Figs. 11 and 12, is a guideway for the shank portion, indicated by the numeral 274, of the channel knife 10. The shank 274 is clamped in a desired po-

sition of adjustment of the knife 10 by a set screw 276. In order to insure that when the knife 10 is removed for grinding, or for any other reason, it may readily be replaced in the position of its former adjustment, a stop 278 is secured to the block 268 by a clamping screw 280. The screw 280 passes through a slot formed in the stop 278 and extending in a direction parallel to the guideway for the shank 274. The stop 278 has a flange 282 which overhangs the end of the shank 274 and thereby definitely limits the extent to which it can be inserted in the guideway upon replacement of the knife. The stop 278 may be clamped in any desired position by the screw 280 to determine the adjustment of the knife 10.

The elevation of the channeling knife relatively to that of the presser foot determines the heightwise position of the channeling cut, and may be varied as desired by adjustment of the screw 254. The inclination of the channeling cut is determined by the adjustment of the block 264 in the arcuate guideway 262. Adjustment of the inclination of the channeling cut does not vary the level, relatively to the thickness of the sole, of the point at which the knife 10 enters the edge of the sole, because the center of the arcuate guideway 262 is taken about that point, which is slightly higher than the upper edge of the periphery of the edge gage wheel 16. The block 268 is adjusted in its horizontal guideway to bring the cutting edge of the knife 10 as close as possible to the presser foot 18, the block being advanced each time the knife is ground to keep the edge close to the presser foot. No adjustment of the knife 10 transversely of the direction of feed is ordinarily made. Such adjustment, however, can be effected by adjusting the position of the frame 172 by means of the screw 184.

Secured by a pair of screws 284 (Fig. 3) to the knife slide block 252 is a block 286 (Figs. 3 and 8) having a vertical guideway in which is secured the foot 132. An adjusting screw 288 having a knurled head 290 is threaded into the block 286. The upper and lower faces of the head 290 engage the walls of a notch formed in the foot 132, thereby determining the position of heightwise adjustment of the latter. A clamping screw 292 passing through a vertical slot in the block 286 clamps the foot 132 to the block. The height of the edge gage roll 16, as has already been pointed out, is determined by the foot 132. The reason for such control over the height of the edge gage roll is to enable the roll to rise and fall in unison with the head 202 to accommodate varying thicknesses of the soles being operated upon, including local variations of thickness in a single sole. Relatively thick soles thus have an abutment of corresponding height, which avoids any tendency of such thick soles to slide over the top of the gage 16. The height of the gage 16, on the other hand, is strictly limited by the small, but necessary clearance for the channeling knife 10. The adjustment of the height of the block 286 by the screw 288 should be such as just to provide this clearance. Since the foot 132 is carried by the channeling knife block 252, heightwise adjustment of the latter will not affect the clearance between the channeling knife and the gage roll.

The grooving knife 12 is mounted in the head 202 by means which will now be described. Slidably mounted for vertical movement in a guideway formed in the head 202 is a block 294 (Figs. 4 and 18). A cover plate 296 retains the block 294 in its guideway. Threaded into the block 294 is an adjusting screw 298 having a head 300

and having also a collar 302 which is engageable with the upper and lower walls of a slot 304 formed in the lug 256 extending from the head 202. A spring 308 embraces a peripheral groove formed in the head 300 to prevent undesired turning of the screw 298. Surrounding the screw 298 and interposed between the upper surface of the lug 306 and the lower face of the block 294 is a compression spring 310 which exerts a downward thrust upon the block 294 to retain the latter in a position of adjustment with the collar 302 bearing against the lower wall of the slot 304. Formed in the lower portion of the block 294 is a horizontal guideway 312 which extends in the direction of the feed of the work. Slidably mounted in the guideway 312 is a block 314 (Figs. 4 and 13). A clamping screw 316 extending through a horizontal slot 317 in the block 314 and threaded into the block 294 secures the block 314 to the block 294. Threaded in the block 314 is an adjusting screw 318 having a knurled head 320. The end of the screw 318 bears against the block 294 and thereby determines the position of horizontal adjustment of the block 314 relatively to the block 294. The screw 318 is provided with a knurled lock nut 322. Upon the lower portion of the block 314 is formed a guideway 324 (Fig. 15) upon which is slidably mounted a block 326. The guideway 324 extends transversely to the direction of the feed of the work, and a clamping screw 328 passing through a slot in the block 326 secures the block 326 to the block 314. Formed in the under surface of the block 326 is an arcuate guideway in which is rotatably mounted a block 330 (Fig. 13) having an arcuate rib 332 which is slidable in the above-mentioned guideway. The block 330 is secured to the block 326 by a clamping screw 334 threaded into the block 326 and passing through a slot in the block 330. Retained within a bore in the block 330 is a draw bolt 336 (Figs. 13, 14 and 16) having a tapered portion 338 (Fig. 16) which engages a complementary tapered surface on the block 330 to lock the bolt 336 against turning when a clamping nut 340 threaded upon the end of the bolt 336 and bearing against the block 330 is tightened. Integral with the bolt 336 is a head 342. Slidably mounted in the head 342 is a shank 344 upon which is secured the tubular grooving knife 12. In the illustrated construction the grooving knife 12 is welded to the shank 344. The shank 344 is retained within its groove by a square washer 346 which is held by a clamping screw 348 threaded into the head 342. It is unnecessary to adjust the shank 344 relatively to the block 342, and in order to insure that the grooving knife will always be secured in the same position relatively to the head 342, a finished surface 350 (Fig. 13) is provided on the head 342. This finished surface 350 constitutes a stop to limit the inward movement of the shank 344 by engagement with the knife 12. Secured upon the head 342 by a screw 351 (Figs. 14 and 16) is a block 353. As shown in Fig. 14, the block 353 has a flange engaging a complementary surface of the head 342 to provide for sliding adjustment of the block 353 parallel to the bolt 336. As also shown in Fig. 14, the block 353 is slotted to accommodate the screw 351 for various positions of adjustment. Secured upon the block 353 by a pair of screws 352 is a guide 354 for the thread of leather which is removed by the grooving knife. It will be noted that the angle of the grooving knife 12 can be adjusted by loosening the screw 334 and

rotating the block 330. The arcuate guideway for the block 330 has its center approximately at the locality of the cutting edge of the grooving knife 12 so that angular adjustment of the grooving 5 knife will not vary the position of its cutting edge.

In some types of work the stitch-receiving groove is omitted around the toe end of the sole and the illustrated machine is accordingly provided with a treadle-operated mechanism whereby the operator can discontinue and resume the groove at will. This mechanism comprises a lever 356 (Figs. 2 and 18) which is fulcrumed upon a pin 358 mounted on the arm 200. The outer end of the lever 256 is connected to a 10 treadle rod 360, the lower end of which is connected to a treadle 362. The inner end of the lever 356 is provided with a pair of spaced ears 364 which embrace a pin 366, secured to the slide block 294. Depression of the treadle 15 20 362 will serve to raise the pin 366 and thereby the grooving knife 12. The purpose of the slot 304, above referred to, is not only to determine the operating position of the grooving knife 12 under the influence of the spring 310, but also to serve as an upper limit to the movement 25 of the grooving knife to prevent the grooving knife from being raised far enough to engage the upper lip. This distance is relatively slight and accordingly the slot 304 is only slightly 30 deeper than the thickness of the collar 302.

It will be noted, referring to Fig. 2, that the line of pull of the treadle rod 360 is relatively close to the axis of the pin 198. Accordingly, 35 operation of the treadle 362 will not tend to swing the head 202 about the pin 198, and likewise movements of the arm 200 occasioned by slight variations in the thickness of the work will not, to any appreciable extent, be transmitted through the rod 360 to the treadle 362.

40 The feed wheel 14 is provided with teeth 368 (Fig. 3) which, as illustrated in Figs. 19, 20 and 21, are obliquely disposed upon the cylindrical surface which constitutes the periphery of the feed wheel. Each of the teeth 368 has a sharp 45 edge or ridge 370 which has the form of a convex curve extending lengthwise of the tooth and rising from the surface of the periphery of the feed wheel. The lateral surfaces of each tooth are generated by a pair of elements 372 and 374, 50 respectively, which pass through the edge 370, each element being maintained substantially parallel to its original position. The form of tooth above described, having a sharp edge 370, is employed in operations upon leather soles, the 55 presser foot 18 bearing down upon the soles with sufficient force to cause the feed teeth to cut into the surface of the leather to their full depth.

For operating upon rubber soles a somewhat 60 different form of tooth 376 illustrated in Figs. 22, 23 and 24 is preferable. The teeth 376 are likewise inclined to the elements of the cylindrical surface which constitutes the periphery of the wheel 14. Each of the teeth 376 has an edge or ridge 378 which extends entirely across the 65 periphery of the feed wheel. The edge 378 is a slightly convex curve and the tooth is generated by a pair of curved elements 380 and 382 which intersect in the edge 378. The rubber soles are pressed against the feed wheel with sufficient 70 force to cause the teeth 376 to become partially embedded in the rubber. The edges 378, however, are not sharp enough to cut into the rubber.

A third form of tooth, indicated by the reference character 384, is illustrated in Figs. 25, 26 75 and 27. The base of this tooth is an oblique

parallelogram (disregarding the curvature of the periphery of the feed wheel, which is negligible over the area of a single tooth), consisting of two parallel short sides 386 and two parallel long sides, one of which is indicated by the reference 5 numeral 388. This tooth has a ridge 390 which is parallel to and equidistant from the long sides 388 of the base. The lateral faces, which are included between the ridge 390 and the sides 388 are substantially plane. The ridge 390 is shorter than the sides 388; and the end faces of the tooth, which are triangular, lie in planes which slope upwardly toward each other from the short sides 386 and at equal angles to the plane of the base. The intersections of the end 10 faces with the lateral faces form edges, and those edges which extend from the ends of the ridge 390 to the acute corners respectively of the parallelogram of the base constitute in effect continuations of the ridge 390 and are designated by the reference character 392. The parallelogram of the base is disposed upon the periphery of the feed wheel with the sides 388 inclined to the elements of the cylindrical surface of the feed wheel; the long diagonal is 15 similarly inclined, but to a less extent. The tooth 384, like the tooth 368, does not extend to either edge of the periphery of the feed wheel. The tooth 384 is an alternative to the tooth 368, and operates in the same way upon leather soles. 20

All of the feed teeth above described are, as has already been mentioned, obliquely disposed upon the periphery of the feed wheel. This obliquity of the feed teeth causes them to exert upon the sole a thrust which is transverse to the 25 direction of feed, urging the sole against the edge gage, and relieving the operator of having to hold the sole against the edge gage. The sole can thus be left to itself and will remain in contact with the edge gage as it is fed, turning 30 according to the various curves in its outline. The pressure of the work against the edge gage resulting from the inclination of the feed teeth not only maintains the work in gaged relation to the operating tools but also, since the edge 35 gage is a driven roll with a knurled edge, enables the edge gage to assist in feeding the work. 40

When a sole as it is being fed is turned in accordance with the curvature of its outline, the turning movement will give rise to components 45 of motion which are lengthwise relatively to the feed teeth. Such components are especially pronounced at the sharply curved toe end of the sole. The tooth 369 is shaped to facilitate such turning movement. The convex ridge 370 not only is adapted to relative pivotal movement, but will cut into the leather as relative endwise movement takes place, without gouging the sole or tearing the fibers of the material and with a minimum of resistance to the relative movement. The tooth 384 will behave in the same way. It 50 will be noted that the ridge 390, together with the edges 392, is similar to the ridge 370, and that the tooth 384 is approximately like the tooth 368. As already mentioned, the teeth 376 are different 55 in that they are more blunt and are not intended to cut into the material; they are not embedded in the material to their full depth, and they extend completely across the periphery of the feed wheel. The teeth 376, however, resemble the 60 teeth 368 and 384 in being obliquely disposed upon the periphery of the feed wheel and in having a convex ridge 378. The end portions of the teeth 376 are not embedded in the material to any 65 appreciable extent, and the convexity of the ridge 70 75 75

378 will accommodate relative longitudinal movement of the work without any gouging of the material by the end portions of the teeth. It is apparent that all three forms of teeth will offer a minimum of resistance to the turning of the sole 5 and avoid damaging the sole when it turns.

To start the machine the operator depresses the treadle 74, latching it down, which couples the power drive of the machine to the feed wheel and causes the sole to be fed in operative engagement 10 with the channeling and grooving knives. The depth of the channel is controlled by the edge gage roll 16. In many types of work where the depth of the channel is to be increased at the 15 shank portion of the shoe the operator depresses the treadle 164 which moves the edge gage roll inwardly and thereby increases the depth of the channel. When the stitch-receiving groove is to be discontinued, the operator depresses the 20 treadle 362 holding it down until the work has been fed to a point where the groove is to be resumed. In certain cases it is desirable that the work be fed slowly and in such cases the operator may release the treadle 66, thereby disconnecting 25 the driving clutch, and turn the wheel 34 by hand. The operator often finds it convenient to control the speed of the feed wheel by grasping the rim 36 and permitting it to slip through his fingers at the desired speed, without resort to the treadle 74.

30 Having thus described my invention, what I claim as new and desire to secure by Letters Patent of the United States is:

1. A sole fitting machine comprising a lower frame, sole-supporting and feeding means on said 35 lower frame, an upper frame, a head supported on said upper frame for movement toward and from said supporting and feeding means, an operating tool on said head, means for urging said head toward said supporting and feeding means, 40 a presser foot carried by said head for supporting said head against said urging means in accordance with the thickness of the work, and means for securing said upper frame fixedly upon said lower frame in a desired position of adjustment transversely of the direction in which the 45 work is fed.

2. A sole fitting machine comprising a lower frame, sole-supporting and feeding means on said lower frame, an upper frame, a head supported 50 on said upper frame for movement toward and from said supporting and feeding means, an operating tool on said head, means for urging said head toward said supporting and feeding means, a presser foot carried by said head for supporting said head against said urging means 55 in accordance with the thickness of the work, means for adjusting said upper frame relatively to said lower frame in a direction transverse to the direction in which the work is fed, and means 60 for securing said upper frame upon said lower frame in adjusted position, said adjusting means being constructed and arranged to insure replacement of said upper frame in a position of previous adjustment after removal from said lower frame.

65 3. In a sole fitting machine, a frame, a head movably carried by said frame, an operating tool mounted in said head, a lever fulcrumed on said frame, a spring acting on said lever, and a strut interposed between said lever and said head for transmitting the thrust of said spring from said 70 lever to said head to urge said head to a desired operating position, said lever and said head having recesses to accommodate the ends respectively of said strut.

75 4. In a sole fitting machine, a frame, a head

movably carried by said frame, a channeling knife mounted in said head, a presser foot mounted in said head, a work support, a lever fulcrumed in said frame, a headed screw threaded into said frame, a compression spring interposed between the head of said screw and said lever, and means for transmitting the thrust of said spring from said lever into said head to urge the presser foot against a work piece on said work support, said screw serving as a means of adjusting the compression of said spring.

5. A sole fitting machine comprising a tool for operating upon a sole, a feed wheel for supporting the sole and feeding the sole past said tool, a driven shaft upon which said feed wheel is mounted, an edge gage for positioning the sole relatively to said tool, a spring urging said edge gage to a stop position, means for retracting said edge gage from said stop position against the force of said spring to vary the position of the sole relatively to the tool, a spring for urging said feed wheel to a stop position, and connections to said edge gage and said feed wheel constructed and arranged to retract said feed wheel from its stop position in unison with said edge gage.

6. In a sole fitting machine, a tool for operating upon a sole, a driven feed wheel for feeding the sole relatively to said tool, a head upon which said tool is mounted with provision for movement of said tool relatively to said head in a direction 30 toward and from said roll, a pivotal support for said head having its axis substantially parallel to the axis of said feed roll to provide for yielding movement of said head away from said feed roll to accommodate the thickness of the work, a 35 lever fulcrumed upon said head for controlling the movement of the operating tool relatively to the head, and an operating rod for said lever, said operating rod having its line of pull relatively close to the axis of said pivotal support to 40 avoid transmitting movement to said head.

7. In a machine for operating upon shoe parts or like articles, a feed wheel having elongated feed teeth disposed obliquely upon its periphery, each of said feed teeth being relatively high at 45 a locality substantially midway between its ends, and the height of each tooth, in the localities adjacent to the ends of the tooth, diminishing toward the adjacent end.

8. In a machine for operating upon shoe parts 50 or like articles, a feed wheel having elongated teeth extending from its periphery, each of said teeth having a ridge which extends lengthwise of the tooth and which is convex in longitudinal section, the end portions of which ridge are lower, 55 with respect to the periphery of the wheel, than the intermediate portion.

9. In a machine for operating upon shoe parts or like articles, a feed wheel having teeth which extend obliquely with respect to their path of 60 movement, each of said teeth having a ridge which extends lengthwise of the tooth and which is convex in longitudinal section, the end portions of which ridge are lower, with respect to the periphery of the wheel, than the intermediate 65 portion.

10. In a machine for operating upon shoe parts or like articles, a feed wheel having obliquely disposed teeth upon its periphery, each of said teeth having a sharp ridge which emerges at 70 each end of the tooth from the peripheral surface of the wheel, said ridge being convexly rounded from one end of the tooth to the other end.

11. In a channeling machine, a grooving knife, a carrier for said knife, a block having an arcuate 75

guide in which said carrier is adjustably secured, the axis of said arcuate guide passing through the locality occupied by the cutting end of said knife, whereby the adjustment of the carrier in said arcuate guideway will not affect the cutting end of the knife.

12. In a channeling machine, a grooving knife, and a support in which said knife is mounted for universal angular adjustment.

10 13. In a channeling machine, a grooving knife, a block, a support for said knife pivotally mounted in said block for tilting adjustment of said knife, and a second block having an arcuate guide in which the first-mentioned block is adjustably secured, the axis of said arcuate guide passing through the locality occupied by the cutting end of said knife, whereby the adjustment of the first-

mentioned block in said arcuate guideway will not affect the position of the cutting end of the knife.

14. In a sole fitting machine, a frame, a feed wheel mounted on said frame, a head constructed and arranged to carry an operating tool, a pivotal support upon which said head is mounted for swinging movement toward and from said feed wheel about an axis parallel to the axis of said feed wheel, a lever mounted on said frame for pivotal movement about an axis transverse to the axis of said pivotal support, a connection between said lever and said head, and resilient means acting through said lever and said connection to urge said head toward said feed-wheel.

NORWOOD H. KNOWLTON.
